United States Patent

Des. 236,710
Patented Sept. 9, 1975

236,710

TIRE

David Lyndon Buck and Anthony Mark Mills, Sutton
Coldfield, England, assignors to Dunlop Limited

Filed Feb. 26, 1973, Ser. No. 335,800

Claims priority, application Great Britain Sept. 1, 1972

Term of patent 14 years

Int. Cl. D12—15

U.S. Cl. D12—144

FIG. 1

FIG. 2

FIG. 3

FIG. 4

FIG. 5

FIG. 6

FIG. 7

FIG. 1 is a plan view of a tire showing our new design, it being understood that the tread pattern is repeated throughout the circumference of the tire;

FIG. 2 is a perspective view thereof;

FIG. 3 is a typical side elevational view thereof;

FIG. 4 is a plan view of a tire showing a second embodiment of our new design, it being understood that the tread pattern is repeated throughout the circumference of the tire;

FIG. 5 is a perspective view of the tire shown in FIG. 4;

FIG. 6 is a side elevational view of the tire shown in FIG. 4; and

FIG. 7 is a fragmentary sectional view of the tires shown in FIGS. 1 and 4.

We claim:

The ornamental design for a tire, as shown and described.
